UNITED STATES PATENT OFFICE.

HOMER C. THRIFT, OF HOUSTON, TEXAS.

WELL-PACKER PLUG.

Application filed April 6, 1923, Serial No. 630,189. Renewed January 5, 1925.

To all whom it may concern:

Be it known that I, HOMER C. THRIFT, a citizen of the United States, residing at Houston, Harris County, Texas, have invented a certain new and useful Improvement in Well-Packer Plugs, of which the following is a full, clear, and exact description, such as will enable others skilled in the art to which it appertains to make and use 10 the same.

My invention relates to a packer plug to be used in sealing off the pressure of fluid from below in a well.

It is desirable, in abandoning a well, to 15 seal off or plug the bottom of the well so that water cannot come up in the well from the bottom to higher levels and permeate other strata which produce oil. In some localities, the rules and laws governing the 20 production of oil require such plugging of the well and even require cementing the same before the casing can be pulled and the well abandoned.

It is an object of my invention to provide 25 a plug which will effectively seal the well and prevent the passage of fluid upwardly in the casing.

Another object is to provide a means of 30 setting such a plug which will work simply and positively, and which will be easy to operate.

Another object is to provide a plug which 35 will effectively prevent the passage of fluid upwardly in the well, but which will allow the bottom of the well to be cemented after the device is set in position.

Other objects and advantages will more 40 clearly appear from the more detailed description which follows.

Referring to the drawing herewith, Fig. 1 is a side elevation, partly in central vertical section of the upper end of the well showing my device therein. Fig. 2 is a central vertical section of my device in expanded 45 position within a well casing. Fig. 3 is an enlarged detail of the packer plug, partly in section, and Fig. 4 is a detail of the setting tool.

The plug, which constitutes the principal 50 portion of my invention, comprises a central tubular mandrel 1, which is tapered upwardly from the lower end, both on its outer and inner diameters, to a point spaced somewhat from the upper end. The upper portion at 2 is cylindrical and has a threaded shank 3 at the extreme upper portion for

attachment to a socket 4, by means of which a setting tool may be releasably connected thereto. The socket 4 has a central opening 5 at the upper end, this opening being 60 recessed at 6 to provide a shoulder 7 against which the setting tool may grip.

On the outer surface of the tapered mandrel, I provide a packing sleeve 8 of some 65 expandible material, and I prefer to use some soft metal, such as lead. This sleeve is preferably slit longitudinally from adjacent the upper end downwardly to a point spaced somewhat up from the lower end. These 70 slits 9 allow the thicker portion of the packing sleeve to better expand against the walls of the casing. I also contemplate forming small gripping teeth 10, embedded in the packer and presenting a serrated outer face against the wall of the casing so as to obtain a firm gripping hold thereon. These 75 teeth are preferably of hardened steel and will act to retain the packer firmly in place.

The central passage 11 through the mandrel is of uniform diameter through the upper portion thereof, and flares out toward the bottom as shown particularly in Fig. 2. Within the flared lower portion, I fit a tapered plug 12 which is adapted to act as a 80 valve during the operation of the device, as will be later explained. The movement of this valve is in a downward direction and is limited by a transverse pin 13.

The packing sleeve 8 firmly rests upon the tapered surface and extends upwardly to a 85 point slightly below the upper end of the cylindrical portion 2. The upper end of the sleeve 8 is beveled around the central opening therein to provide a tapered seat for an expanding ring 14 shaped like an inverted cone and fitting slidably upon the cylindrical portion 2 of the mandrel. Said ring acts to 90 protect the packer before expansion. The ring 14 is held at the upper end of said cylindrical member 2 by pins 15 extending radially through the ring and secured within the mandrel. These pins are made of some 95 soft or frangible material so that they are broken or sheared off when a hard blow is 100 delivered against the plate.

The setting tool, by means of which the 105 plug is lowered to the bottom of the well, comprises a head 16, which is cylindrical in general form and tapered upwardly at its upper end 17. Extending downwardly 110 from the head 16 is a plurality of resilient arms 18, of which I have shown three in

number. At their lower ends, these spring arms are beveled outwardly to provide releasing lugs 19. Below these lugs, the arms are extended downwardly and have latch members 20 at the lower ends provided with upper shoulders 21 adapted to engage beneath the shoulders 7 in the socket 4. The resiliency of the arms tends to hold these latch members outwardly so that, when 10 the same are engaged within the socket 4, they will automatically remain in place until released. A suspending cable 22 is secured centrally within the head 16 of the setting tool and is secured therein by any 15 ordinary means.

The releasing member which is used in connection with my plug is shown particularly in Fig. 2. It comprises a length of pipe 23 of an interior diameter sufficient to 20 telescope over the socket 4 at the upper end of the plug. It is tapered inwardly at 24 toward the upper end, and has a shank 25 of small diameter above the tapered portion. The cable is adapted to extend downwardly 25 through the smaller diameter and the releasing device may be suspended upon the setting tool in the manner shown in Fig. 1 for raising or lowering the releasing member in the well.

30 In the use of my device, I install a gate valve 26 at the upper end of the casing and above this valve a special nipple 27 is secured. This nipple is of sufficient interior diameter to include the plug, the setting 35 tool and the releasing sleeve therein. On one side of the nipple, I provide a similar gate valve 28 for testing purposes. Inside the nipple, above the valve 28, are two diametrically arranged screws 29 set in 40 bosses 30 in the side of the nipple, having a fluid-tight connection with the walls of the boss by means of the stuffing box 31. There are two of these screws 29, although 45 it is obvious that one might answer the purpose for which they are designed. These screws project inwardly and fit within openings 32 in the side of the releasing sleeve and serve to hold it in elevated position at the upper end of the nipple as shown 50 in Fig. 1. The cable 22 extends upwardly through a closure plate 33 and maintains a close sliding fit therewith by means of a stuffing box 34.

55 In the operation of this device, the tool will be assembled in the nipple 27 in the manner shown in Fig. 1. The setting tool will be engaged within the socket 4 at the upper end of the plug and will be suspended 60 within the nipple. The releasing sleeve 23 will be secured by means of the supporting screws 29 in position at the upper end of the nipple. While this installation is being made, the gate valve 26, of course, will be closed to shut off the high pressure from 65 the lower portion of the well. When the

70 installation has been properly made, the cap 33 will be secured on the upper end of the nipple so as to prevent the escape of fluid at that point and the valve 28 closed. When this has been done, the gate valve 26 75 may be opened and the device lowered past the valve down through the casing to the desired position in the well. The fluid present in the well will not interfere with the lowering of the device. When the plug 80 is dropped downwardly through the liquid in the well, the packer sleeve 8 will be in contracted position and the water will escape upwardly around the outer face thereof and some of the same will find an outlet 85 past the valve 12 through the channel 11. When the plug is in position the setting tool will be released. This operation is performed by dropping the releasing sleeve 23. The screws 29 are retracted by unscrewing 90 them so that the sleeve will drop. It will pass downwardly in the casing striking a blow upon the beveled upper face of the lugs 19, thus forcing the latches 20 inwardly and releasing them from the socket 4 so that they may be drawn upwardly. The downward drop of the sleeve 23 will also deliver a blow upon the expanding ring 14 and serve to break the pins 15 so as to force 95 the ring to move downwardly and expand the packer 8 in an obvious manner. If the first blow of the falling sleeve 23 does not expand the packer the sleeve may be raised by means of the cable and the setting tool and again suddenly dropped. In this manner, blows may be delivered on the expanding ring and the packer until said packer is firmly expanded, against the casing. The ring will not only wedge the upper end of the packer outwardly, but will force the packer downwardly on the mandrel and thus also further expand it. To 100 test whether the seal has been properly made, the valve 28 may be opened to see if there is an upward pressure tending to force the liquid out and if it is found that pressure still exists, it will be understood that the packer is not properly expanded and further pounding upon the packing member may be accomplished by the use of the releasing sleeve 23 in the manner described. 105

110 It is often desired to cement the bottom of the well after the plug has been set. This may be accomplished with my device by removing the setting tool and releasing sleeve from the wall and forcing the cement, under high pressure, downwardly through the casing and through the passage 11 in the plug past the valve 12 into the bottom 115 of the well. When the well below the plug has been properly cemented and allowed to set, it is possible to cement again above the plug if desired in an obvious manner.

120 The advantages of my device will be apparent to one skilled in the art. The plug 125

may be easily and positively expanded so as to seal the bottom of the well, and after it has been set it is still possible to cement both above and below the plug. The setting

5 tool with its releasing device is positive in its operation and will not fail to work under ordinary circumstances.

Having thus described my invention, what I claim as new and desire to protect by Letters Patent, is:

10 1. In a device of the character described, a central mandrel tapered upwardly from the lower end, a packing sleeve of soft compressible material fitting on said mandrel, an expanding ring adjacent to the upper end of said tapered mandrel, releasable means to secure said ring to said mandrel, a socket on the upper end of said mandrel, releasable setting means adapted to engage 15 within said socket, and a releasing sleeve adapted to release said setting means, said ring and to expand said sleeve.

20 2. In a device of the character described, a central tubular mandrel tapered upwardly from the lower end, a packing means on said mandrel adapted to be expanded when moved downwardly thereon, an expanding ring on said mandrel adjacent the upper end of said packing means, frangible means 25 securing said ring to said mandrel, means to lower said device within the well and means to expand said packing means, comprising a sleeve adapted to drop within the well to release said ring and expand said 30 packing sleeve.

35 3. In a device of the character described, a central tubular mandrel tapered upwardly from the lower end, a packing sleeve of compressible material fitting on said mandrel, means to help expand the packing sleeve at the upper end of said sleeve, a socket on the upper end of said mandrel, releasable setting means adapted to latch within said socket, means to release said setting means and expand said packer, and a downwardly opening valve within said mandrel.

40 4. In a device of the character described, a central tubular mandrel, packing means on the outer surface thereof, a socket at the upper end of said mandrel, a releasable setting tool adapted to lower said mandrel in the well, a releasing sleeve adapted to release said setting tool and expand said packer and means to prevent the passage of fluid upwardly through said mandrel.

45 5. In a device of the character described, a central tubular mandrel tapered upwardly from the lower end, a packing sleeve of soft metal fitting on said mandrel, said sleeve

being slit longitudinally along its central portion, a ring adjacent the upper end of said tapered mandrel, frangible means securing said ring to said mandrel, a socket on the upper end of said mandrel, releasable 65 setting means adapted to fit in said socket to lower the same into the well, and a releasing sleeve adapted to release said setting means and to expand said packing sleeve on said mandrel.

70 6. In a device of the character described, a central tubular mandrel, packing means on the outer surface thereof, means comprising a tapered ring connected to said mandrel to protect said packing while said plug is being introduced into the well, and additional means to disconnect said protecting means and expand said packing.

75 7. In a device of the character described, a central mandrel tapered upwardly, an expandable packing means thereon, means above said packing means to protect the same, a releasing sleeve adapted to strike a blow on said protecting means to release the same and to expand said packing, and 80 a downwardly opening valve in said mandrel.

80 8. In a packer plug for wells, a mandrel, a packing means on said mandrel, a setting tool releasably connected with said mandrel, and a sleeve adapted to release said setting tool from said mandrel and expand said packer.

85 9. In a device of the character described, a mandrel, packing means thereon, means to set said plug in position in combination with a releasing sleeve, and means to normally retain said sleeve at the upper end of the well, said sleeve being adapted when dropped to release the setting means and also to 90 expand said packing means.

95 10. In a device of the character described, an upwardly tapered mandrel, a packing sleeve thereon of compressible material, teeth of hard material in the outer surface 100 of said sleeve, means to protect said sleeve from accidental expansion, and additional means to release said protecting means and expand said packing sleeve.

110 11. In a packer plug for wells including a mandrel, a packing sleeve thereon, means releasably connected to said mandrel acting normally to protect said packing means and separate means to drive said protecting means down and expand said packing.

115 In testimony whereof I hereunto affix my signature this the 2nd day of April, A. D. 1923.

HOMER C. THRIFT.
